United States Patent Office.

JOHN F. WORTH, OF BROOKLYN, NEW YORK, ASSIGNOR TO HIMSELF, IRA W. GREGORY, AND ALFRED GREGORY, OF SAME PLACE.

Letters Patent No. 96,069, dated October 19, 1869.

IMPROVED TESSELLATED FLOOR.

The Schedule referred to in these Letters Patent and making part of the same.

To all whom it may concern:

Be it known that I, JOHN F. WORTH, of the city of Brooklyn, in the county of Kings, and State of New York, have invented a new and useful Improvement in Slabs and Blocks for Tessellated Floors; and I do hereby declare that the following is a full, clear, and exact description of the same, reference being had to the accompanying drawings, which form part of this specification.

This invention relates to the securing together of slabs or blocks of tessellated wooden floors by tongues and grooves.

Said slabs or blocks, if constructed with their tongues or tenons on them, or provided with tongues of the same material, would require unnecessary depth or thickness of the block for insuring a sufficiency of strength to the tongue, more especially when the blocks are constructed for presenting the end of the grain to the wearing-surface.

My improvement consists in providing each block with an angularly-formed metal tongue, which projects from two or more of its sides, according to the form of the block, and forming in its remaining sides corresponding grooves, for reception of the metal tongues of the blocks adjoining those sides, whereby a considerable reduction in the thickness of the blocks may be afforded without reducing the strength of their connections.

Referring to the accompanying drawings,

Figure 1 represents a portion of a tessellated floor formed of blocks constructed according to my invention;

Figure 2 represents a face view of one of the blocks, detached;

Figure 3 represents an edgewise view of the same; and

Figure 4, a sectional view of one of the blocks, taken in the line $z z$, fig. 3.

Similar letters of reference indicate corresponding parts in the several figures.

A A, &c., are square wooden blocks, of any suitable size, and fitted together, as shown in fig. 1.

Each one of said blocks A has a deep narrow groove, s , formed in its edge, on all four of its sides.

Within this groove s , used upon two sides of the block, when square blocks are fitted and secured by glue, cement, or other suitable means, is a rectangularly-formed metal tongue, a , as shown, the groove on the remaining sides of the block being left open, for the reception of the metal tongues of the blocks adjoining thereto.

Said rectangular tongue a , being constructed of metal, is proportionately much stronger than wooden tongues, and consequently may be made much thinner, as shown in fig. 3, thereby allowing the block itself to be made thinner, as also shown in the same figure.

With floors formed of blocks constructed after this plan, a much greater depth or thickness of material may also be left between the outer surface of the floor and the said tongues a , for the wearing away of the floor, than is practicable with floors formed of blocks of equal thickness constructed with wooden tongues.

The invention may also be applied to blocks of hexagonal and other forms, by giving the metal tongues a form to correspond with that of the blocks to which it is to be applied.

What is here claimed, and desired to be secured by Letters Patent, is—

The angular metal tongues, in combination with the blocks or slabs of wooden tessellated pavement, substantially as described, for the purpose set forth.

JOHN F. WORTH.
